POWER-DRIVEN OSCILLATING ERASER

Paul C. Hutton, Washington, D. C.

Application November 20, 1947, Serial No. 787,077

7 Claims. (Cl. 120—36)

1

This invention relates to an eraser and more particularly to an oscillating eraser adapted to be held in the hand of the user during the erasing operation.

The primary object of the invention is to enable a mechanical erasing operation to be directly under the control of the user so that the degree of pressure applied to the material being erased may be governed with exactness.

Another object is to facilitate the rapid interchange of erasers in a mechanical erasing device should one become worn through use, and to enable fresh and unused erasers easily to be substituted for any which have become unserviceable for any reason whatsoever.

A further object is to enable the driving spring of a mechanical eraser easily to be wound with a minimum amount of effort on the part of the user.

A still further object is to place within the grasp of the user control mechanism by which the oscillations of the eraser may be arrested as soon as the erasing operation has been completed, and also to reduce the speed of the oscillatory motion of the eraser to avoid a too rapid de-energization of the spring.

The above and other objects may be attained by employing this invention which embodies among its features an elongated tubular body, a rocker arm supported in said body to oscillate about an axis which lies perpendicular to the longitudinal axis of the body, an eraser supported on the rocker arm for movement beyond one end of the tubular body and means at the opposite end of the tubular body for imparting oscillatory motion to the rocker arm.

Other features include manually actuated means on the tubular body near the end adjacent the eraser for arresting oscillatory motion of the rocker arm, a governor on the body to reduce the rapidity with which the rocker arm oscillates, and means to change the position of the fulcrum point around which the rocker arm oscillates thereby to govern the length of stroke of the eraser.

Still other features involve pivotally mounting on the end of the rocker arm remote from the drive means a reversible eraser carrier having on opposite ends means detachably to connect an eraser thereto, and a spring actuated drive motor including a spring driven winding drum upon which an eraser actuating tape is wound, a zig-zag cam track extending longitudinally of the tape, and means coupling the end of the rocker arm remote from the eraser to the tape for en-

2

gagement in the cam track by which the oscillatory motion of the rocker is produced as the tape is wound upon the drum.

In the drawings:

Figure 1 is a perspective view of an eraser embodying features of this invention,

Figure 2 is a broken longitudinal sectional view on a somewhat enlarged scale through the eraser illustrated in Figure 1,

Figure 3 is a view similar to that of Figure 2 taken substantially in a plane perpendicular of Figure 2,

Figure 4 is a fragmentary perspective view partially in section on an enlarged scale of the lower end of the eraser,

Figure 5 is a fragmentary perspective view on an enlarged scale of the upper end of the eraser,

Figure 6 is a horizontal sectional view taken substantially along the line 6—6 of Figure 2,

Figure 7 is a transverse sectional view taken substantially along the line 7—7 of Figure 6,

Figure 8 is a fragmentary plan view of the driving tape illustrating the zig-zag cam track therein.

Figure 9 is a perspective view of the rocker arm, and

Figure 10 is a side view of the rocker arm pivot.

Referring to the drawings in detail, this improved eraser embodies an elongated tubular body 10 provided at one end with diametrically arranged longitudinally extending arms 12 which are pierced adjacent their ends, remote from the body 10 with aligning rectangular openings 14 for a purpose to be more fully hereinafter explained. Entering the end of the body remote from the arms 12 at diametrically opposite points are elongated slots 16 which are arranged in axial alignment with the arms 12. Formed in the body adjacent the end containing the slots 16 and extending through the wall of the body along an axis perpendicular to the plane of the axes of the slots 16 is an opening 18 provided adjacent its lower edge with an inturned cam 20, the purpose of which will be more fully herein-after explained.

Formed in the body intermediate its ends are pairs of diametrically opposed aligned openings 22, 24 and 26, and extending between the openings on each side of the body are longitudinal slots 28. The axes of the openings 22, 24 and 26 lie in a longitudinal plane which lies perpendicular to the axes of the openings 14 and formed in the body adjacent the end carrying the arms 12 is a transverse slot 30 which aligns axially with an indentation 32 which opens into

53

the interior of the body. Extending transversely through the body and offset to one side of the longitudinal axis thereof are spaced, parallel guide bars 34, the outer ends of which project through the body and are headed over to form stops for a sliding sleeve to be more fully hereinafter described. These guide bars 34 are arranged in spaced parallel relation and serve as guides for the oscillating arm to be described hereinafter.

Extending transversely through the body 10 is a pivot pin 36 which comprises a cylindrical stem 38 having adjacent opposite ends cylindrical heads 40 and 42. A conical portion 44 is formed at the junction of the stem 38 and the head 40, and formed on the head 42 on the side remote from the stem 38 is a conical portion 46, the convergent end of which terminates in a cylindrical extension 48 of a length sufficient to accommodate the thickness of the wall of the tubular body 10. Extending longitudinally from the head 40 in the direction opposite the stem 38 is a cylindrical portion 50 which, like the portion 48, is of a length sufficient to accommodate the thickness of the wall of the tubular body 10, and formed at the end of the extension 50 is a conical portion 52 which terminates at its larger end in a cylindrical portion 54. The pivot pin 36 is provided at its extreme opposite ends with heads 56 which, as illustrated in Figure 2, lie on the outside of the cylindrical body 10 to serve as thumb pieces by which the pivot may be shifted along its longitudinal axis and transversely of the tubular body 10. By shifting the pivot to the left when viewed as in Figure 2 it will be obvious that the extensions 48 and 50 will be moved to align with the wall of the body 10 so that the pivot may be shifted longitudinally through the slots 28 into a position to align with the different pairs of openings 22, 24 and 26. When the pivot has been brought into alignment with any group of the above mentioned openings, it may again be shifted to the right when viewed in Figure 2 so that the cylindrical members 42 and 54 will align with the opposite sides of the wall of the cylindrical body 10 and thus hold the pivot against longitudinal movement in the body.

Supported on the pivot 36 within the tubular body 10 is a rocker arm 58 which is provided intermediate its ends with longitudinally spaced transversely extending openings 60, 62 and 64 which align respectively with the openings 22, 24 and 26 in the body 10. This rocker arm is movable between the guides 34, and extending longitudinally through the rocker arm between the openings 60, 62 and 64 are longitudinal slots 66. The openings 60, 62 and 64 are of a size to receive the cylindrical portion 40 of the pivot pin 36 and the slots 66 are of a width sufficient to accommodate the stem 38 of the pivot pin 36. It will thus be seen that when the pivot pin 36 is shifted longitudinally of the tubular body 10 it also may be shifted longitudinally through the rocker arm 58 in order to regulate the swing of the eraser which is carried by the rocker arm without in any way altering the length of motion of the opposite end of the rocker arm. Riveted or otherwise fixed to one end of the rocker arm 58 is an actuating arm 68 which terminates adjacent its upper end in a reduced neck 70 on the upper end of which is fixed an angularly extending enlarged head 72.

Pivotedly supported adjacent the end of the rocker arm 58 remote from the actuating arm 75

68 to swing about an axis which lies perpendicular to the longitudinal axis of the rocker arm is an eraser carrier 74. This eraser carrier constitutes a straight bar of metal or the like, the pivot point of which is located midway between opposite ends, and riveted or otherwise fixed to the arm 58 between the eraser carrier 74 and the arm is a retaining spring 76, which extends beyond the end of the rocker arm 58 and carries a latch pin 78 which is adapted to enter sockets 80 formed in the adjacent side of the eraser carrier 74. The extreme end of the latch spring 76 is curved outwardly as at 82 to facilitate the withdrawal of the pin 78 from a socket 80 to permit the carrier 74 to be swung around the axis of its pivot. A sleeve or socket member 84 is fitted over each end of the eraser carrier 74, and is frictionally held thereon so that it may be removed and another substituted therefor when conditions so require. Each sleeve 84 is equipped at its end remote from the carrier 74 with any suitable erasing substance 86 such as fiber glass or the like.

Riveted or otherwise attached to the exterior of the cylindrical body 10 adjacent the end containing the opening 18 is a leaf spring 88 having an angularly extending end 90 having convergent sides as illustrated in Figure 4 which when the spring is extended as illustrated lies adjacent one side of the rocker arm 58 to hold it against oscillatory motion about the pivot 36. When, however, pressure is applied to the exterior of the spring 88, the tongue or arm 90 will ride against the cam 20 through the opening 18 so that it may be forced upwardly to lie substantially parallel with the inner side of the wall of the tubular member 10 and clear the rocker arm 58 so as to permit oscillation thereof. It will thus be seen that by pressing the finger against the spring 88, or releasing pressure on the spring the oscillation of the rocker arm 58 may be controlled.

Mounted for longitudinal sliding movement on the tubular body 10 between the heads of the guide pins 34 and the slotted end of the body is a sleeve 92 which is provided with a longitudinal slot 94 which opens through one end to accommodate the spring 88, and this sleeve serves to close the slots 16 under normal operating conditions. The sleeve, however, may be slid upwardly on the body 10 until the end thereof remote from the eraser 86 engages the heads of the cross pins 34, at which time the slots 16 will be cleared to permit the eraser carrier 74 to be swung about its pivot so as to present a new erasing surface to a position for operation. The sleeve 92 may then be returned to the position illustrated in Figures 1, 2 and 3.

Mounted in the rectangular openings 14 are the squared ends of a shaft 96 upon which a pair of spaced guide disks 98 are mounted. These guide disks are held in spaced parallel relation by a cylindrical drum 100, and fixed to the shaft 96 is one end of a spiral spring 102, the opposite end of which is fixed to the inner side of the drum 100 so that when the drum is rotated in one direction, the spring will be placed under tension. Fixed to the drum 100 is one end of a tape 104 which as illustrated in Figure 8 is provided with a longitudinally extending zig-zag cam track 106. In the preferred form of the invention, the cam track 106 constitutes a slot cut through the tape 104 through which projects the neck 70 adjacent the head 72 of the operating arm 68 of the rocker arm 58. This tape 104 is preferably so tensioned that it will tend to roll upon itself,

and fixed to the end of the tape remote from that which is connected to the drum 100 is a magazine reel 108 having extending therethrough an axle 110, the ends of which project well beyond opposite sides of the reel to form finger grips by means of which the tape may be drawn and unreeled from the drum in order to tension the spring 102. Opposite ends of the cam track 106 open into enlarged openings 105 and 107 the purpose of which will more fully hereinafter appear.

Fixed to the tubular body 10 adjacent the arms 12 is a bracket 112 which carries at its upper end a laterally projecting arm 114, the opposite side edges of which are provided with upturned guide flanges 116 which serve as guides for the tape 104. The end edges of the guide flanges 116 remote from the reel or drum 100 are provided with notches 118 in which the shaft 110 is received as illustrated in Figure 1.

Extending laterally from the lower end of the bracket 112 is an arm 120 provided adjacent opposite side edges with upturned supporting arms 122 which are pierced with aligning openings 124 for the reception of a longitudinally moving piston rod 126. A cylinder 128 is fixed to the arm 120, and fixed to the piston rod and operable within the cylinder 128 is a piston 130. The opposite ends of the cylinder are provided with aligning openings 132 through which the piston rod 126 extends, and fixed to opposite ends of the piston rod are the arms 134 of a U-shaped piston actuating member 136. Pivottally connected to the actuating member 136 midway between the arms 134 is one end of an oscillating arm 138 which as illustrated in Figure 2 projects through a transverse slot in the bracket 112 which registers with the slot 30 in the tubular body 10. This lever 138 is provided intermediate its ends with a slot 140 for the reception of the neck 70 on the actuating arm 68 of the rocker arm 58, and the end of the lever 138 remote from that which is connected to the frame 136 is pointed as at 142 to seat in the indentation 32 as will be readily understood upon reference to the drawings. It will thus be seen that the lever 138 will be rocked about its junction with the indentation 32 as the rocker arm 58 is driven through the medium of the cam track 106 in the tape 104. It will also be understood that the movements of the piston 130 within the cylinder 128 will serve to compress the air in opposite ends of the cylinder, thus forming a pneumatic governor by means of which the speed of oscillation of the rocker arm 58 will be retarded.

In use, the operator in order to energize the spring 102 grasps the opposite ends of the shaft 110 of the reel 108 and by turning his wrist lifts the tape or ribbon 104 so that the head 72 will pass through the opening 105 so as to enable the tape 104 to be unwound from the drum 100 without oscillating the rocker arm 58. When the ribbon or tape 104 has been fully unwound from the drum the tubular body 10 is tilted in a reverse direction to cause the head 72 to enter the opening 107 in the ribbon 104 so that as the ribbon again tends to wind about the drum 100 under the influence of the spring 102 the cam track 106 therein will re-engage the neck 70 of the actuating arm 68 beneath the head 72. Obviously the unwinding of the tape 104 from the drum 100 will cause the spring 102 to wind about the shaft 96 and after the tape has been pulled out to its fullest extent, the spring will be fully wound and will so remain until pressure is applied to the

spring 88, so as to cause the tongue 90 to move into a position to disengage the rocker arm 58. Since the tape 104 is of the type that is self-winding it is obvious that by moving the magazine 5 or reel 108 toward the drum 100, the tape will wind about the shaft 110 and hence becomes stored in the magazine. The device is now ready 10 for use and when it is desired to set the eraser in operation, pressure is applied to the spring 88, 15 thus causing the tongue 90 to fold upwardly through contact with the cam 20 so as to clear the rocker arm 58 and permit the arm to oscillate under the influence of the movement of the tape as it is wound upon the drum 100 under the influence of the spring 102. Obviously, the actuating arm 68 will oscillate about the axis of the pivot 36 as the opposite walls of the zig-zag cam track 106 contact opposite sides of the neck 70. By shifting the pivot pin 36 into the different 20 groups of openings in the tubular body 10 and the rocker arm 58, it is obvious that the length of stroke of the eraser may be governed. When it is desired to replace a worn eraser with a new one, it is only necessary to remove the eraser 25 carrying socket 84 from the eraser carrier 74, and one or the other of the erasers 86 carried by the carrier may be substituted for the other simply by sliding the sleeve 92 upwardly along the tubular body 10 so as to clear the slots 16. After 30 having thus cleared the slots, the only other operation that becomes necessary is to withdraw the pin 78 from the recess or socket 80 and swing the carrier into a reverse position after which the pin may be re-entered into the recess 80 in 35 the opposite arm of the carrier and the sleeve 92 returned to its original position.

While in the foregoing there has been shown and described the preferred embodiment of this invention, it is to be understood that minor 40 changes in the details of construction, combination and arrangement of parts may be resorted to without departing from the spirit and scope of the invention as claimed.

Having described the invention, what is claimed 45 as new is:

1. A power driven oscillating eraser comprising an elongated tubular body, a rocker arm supported in said body to oscillate about an axis which lies perpendicular to the longitudinal axis 50 of said body, an eraser supported on the rocker arm for movement therewith beyond one end of the tubular body, means at the opposite end of the tubular body and connected to the rocker arm for imparting oscillatory motion thereto, and a 55 pneumatic governor on the body and connected to the rocker arm to reduce the rapidity with which the rocker arm oscillates.

2. A power driven oscillating eraser comprising an elongated tubular body, a rocker arm supported in said body to oscillate about an axis which lies perpendicular to the longitudinal axis of said body, an eraser supported on the rocker arm for movement therewith beyond one end of the tubular body, a spring loaded drum rotatably 65 supported adjacent the end of the body remote from that through which the eraser operates, a roll of tape mounted near the drum, one end of the tape being connected to the drum for winding thereon under the influence of the spring 70 therein, said tape having a zig-zag longitudinal cam track therein and means on the rocker arm for engaging the cam track and oscillating the arm as the tape is wound upon the drum.

3. A power driven oscillating eraser comprising 75 an elongated tubular body, a rocker arm support-

ed in said body to oscillate about an axis which lies perpendicular to the longitudinal axis of said body, an eraser supported on the rocker arm for movement therewith beyond one end of the tubular body, a spring loaded drum rotatably supported adjacent the end of the body remote from that through which the eraser operates, a roll of tape mounted near the drum, one end of the tape being connected to the drum for winding thereon under the influence of the spring therein, said tape having a zig-zag longitudinal cam track therein, means on the rocker arm for engaging the cam track and oscillating the arm as the tape is wound upon the drum, and means detachably supported on the tubular body adjacent the drum upon which the roll of tape is supported for unreeing said tape from said drum to tension said spring.

4. A power driven oscillating eraser comprising an elongated tubular body, a pivot mounted intermediate the ends of the body for adjustment longitudinally thereof, a rocker arm mounted on the pivot for oscillatory motion within the body, an eraser carrier on one end of the rocker arm for movement therewith beyond one end of the body, a spring loaded drum rotatably supported adjacent the end of the body remote from the eraser, a tape connected at one end to the drum for winding thereon under the influence of the spring contained in said drum, said tape having a zig-zag longitudinal cam track therein and means on the rocker arm for engaging the cam track and oscillating the arm as the tape is wound upon the drum.

5. A power driven oscillating eraser comprising an elongated tubular body, a rocker arm supported in said body to oscillate about an axis which lies perpendicular to the longitudinal axis of said body, an eraser supported on the rocker arm for movement therewith beyond one end of the tubular body, a spring loaded drum rotatably supported adjacent the end of the body remote from that through which the eraser operates, a roll of tape mounted near the drum, one end of the tape being connected to the drum for winding thereon under the influence of the spring therein, said tape having a zig-zag longitudinal cam track therein, means on the rocker arm for engaging the cam track and oscillating the arm as the tape is wound upon the drum, and a reel detachably supported adjacent the body upon which the tape is stored prior to its winding upon the drum.

6. A power driven oscillating eraser comprising an elongated tubular body having diametrically opposed rows of longitudinally spaced aligned openings extending therethrough, an elongated rocker arm within said tubular body, said rocker arm having a longitudinal row of longitudinally spaced openings therein which align with the openings in the tubular body, an eraser carried by one end of said rocker arm and movable in an arc without said tubular body adjacent one end thereof, means carried by the body and connected with the rocker arm adjacent the end thereof remote from the eraser to oscillate said rocker arm within said tubular body and a pivot pin removably entering one group of aligned openings in the body and rocker arm rockably to support the rocker arm in said body, said pivot pins being adapted to be moved to another row of openings to vary the amplitude of movement of the eraser.

7. A power driven oscillating eraser comprising an elongated tubular body, a rocker arm supported in said body to oscillate about an axis which lies perpendicular to the longitudinal axis of said body, an eraser supported on the rocker arm for movement therewith beyond one end of the body, means at the opposite end of the tubular body and connected to the rocker arm for imparting oscillatory motion thereto, a cylinder carried by the tubular body, a piston working within said cylinder and connected to the rocker arm, and heads carried by and closing opposite ends thereof to confine air therein and retard the speed at which the rocker arm oscillates.
